UNITED STATES PATENT OFFICE.

FRANCIS D. DONOGHUE, OF BOSTON, MASSACHUSETTS.

FOOTWEAR.

No. 915,082.

Specification of Letters Patent. Patented March 16, 1909.

Application filed January 25, 1908. Serial No. 412,531.

To all whom it may concern:

Be it known that I, FRANCIS D. DONOGHUE, a citizen of the United States, and a resident of Boston, in the county of Suffolk and State 5 of Massachusetts, have invented certain new and useful Improvements in Footwear, of which the following is a specification.

This invention relates to footwear.

More particularly, it relates to coverings 10 for the human foot having an upper portion which passes over the instep and a sole under the foot, all such footwear being included in the term "shoe" as here used.

The purpose of the invention is to eliminate certain structural features customarily 15 present in shoes as now made and worn, tending to injure or deform the foot, and to introduce certain novel features which are beneficial and preservative in tendency.

20 The invention provides a shoe in which the constrictive effect of the upper tends to maintain and even to increase the arch formation of the bones of the foot, instead of tending to break down or flatten it. This is 25 accomplished by attaching the upper at the instep to the shank portion of the sole only on the outer edge of the foot. The edge of the upper which has heretofore customarily been attached on the inside of the foot is carried 30 under the foot and attached beneath the outside of the foot.

In the accompanying drawings, Figure 1 is a representation of the bones in a human foot as shown in side elevation in a radiograph, the foot being represented as wearing 35 a shoe shown partly in section. Fig. 2 shows the bottom of a shoe embodying the invention, in process of construction. Fig. 3 represents in end elevation, somewhat diagrammatically, the middle portion of a foot 40 wearing a shoe made according to the invention, sectioned on the line 3—3 of Fig. 1, the section being taken just back of the apex of the middle transverse arch of the foot, showing 45 the relation of the upper sole to that arch. Fig. 4 is a diagram of forces in Fig. 3; and Fig. 5 is a corresponding diagram of the forces in shoes not embodying the invention, as ordinarily constructed.

50 In shoes as ordinarily heretofore constructed, the upper runs from the sole on one side of the foot over the middle transverse arch of the foot down to the sole on the other side of the foot. At the shank of the sole 55 there is an appreciable and considerable

width of stiff material comprised in the sole, under the arch of the foot and intervening between the edges of the upper that terminate on the two sides of the foot. The arch referred to is that running across the 60 foot at or near the apex of the longitudinal antero-postero arch. It may be recognized by the bone which projects upward on the foot about in the middle of the lacing of all 65 low shoes as usually now constructed. At this place the foot has five longitudinal bones arranged side by side in the form of an arch approximately as represented in Figs. 3, 4 and 5, the inner base of the arch being 70 higher than the outer. The under side of the foot curves upward in a manner corresponding somewhat to this arch of bones. In wearing a shoe the foot is thrust between the upper and the sole and is then bound 75 down upon the sole by tightening and fastening the upper with strings or buttons. The tightening of the upper depresses the foot toward the sole and thus tends to depress and flatten the arch of the foot by drawing it tight against the breadth of sole 80 underlying it. When a forward step is taken the arch of the foot has to rise from the ground. As the toes remain on the ground, this is impossible unless the sole of the shoe is bent correspondingly. The resistance of the sole to bending, transmitted 85 through the upper and imposed on the top of the arch of the foot, constitutes an additional force acting at each step with a tendency to break down the arch. The nature 90 of this action is illustrated in the diagram Fig. 5. The resistance of the sole and the constriction due to lacing are like forces pulling downward upon the arch as indicated by the arrow, tending to destroy it. 95 The invention provides a structure in which, contrary to this, the forces tend to form the arch or to preserve it, as will be seen by reference to the diagram of Fig. 4. The forces in that figure tend to draw the bone 100 at the upper end or base of that arch toward the bone at the other end or base. The more tightly the lacing is drawn the more the curvature of the arch is increased. Likewise, in taking a forward step, the resistance of the sole to bending, when transmitted and applied to the arch, tends to draw the upper base toward the lower base, thus strengthening the arch. The strength 105 of the longitudinal arch depends consider- 110

ably on the maintenance of the curvature of the transverse arch. When the latter is flattened the longitudinal arch can break down more easily than when its cross section, 5 as represented by the form of the transverse arch, is well curved. Therefore, the invention tends also to strengthen the longitudinal arch.

In applying the principles above set forth 10 the design and construction of shoes may proceed in general as heretofore, except that the sole and upper are shaped so that, for the right shoe, both right and left edges of the upper are attached to the shank of the 15 sole at the right side of the foot; and for the left shoe both right and left edges of the upper are attached to the shank of the sole under the left side of the foot.

The invention is here illustrated as it may 20 be applied to a welt shoe; but it is applicable to shoes made by any other method including, for example, turned shoes, McKay sewed shoes and pegged shoes; and the word "sole" as used here and in the claims may refer 25 either to the single sole of a turned shoe or to the combined outer and inner soles if a shoe have both. As here illustrated (Fig. 2) the upper 9 and its inner lining 8 are represented as sewed to an inner sole 10 and a 30 welt 12, the inner sole being channeled for this purpose in the ordinary manner as represented at 11. At the shank 13 the edge 14 of the upper, which is on the inner side of the foot, comes as close as possible to the edge 35 15 of the upper which is on the outer side of the foot. The shank of the inner sole which receives these edges is made very narrow, bringing the edges of the upper as near together as the width of the intervening two 40 channels will permit. For this purpose the inner sole is deeply recessed on the right side for the left foot and on the left side for the right foot. This recess runs forward conformably to the shape of the foot about 45 to the inner end of the middle transverse arch of the foot. The last is shaped accordingly. By this construction, the part of the footwear that incases the middle portion of the foot consists practically wholly of soft 50 leather of the upper, which underneath the foot takes the place heretofore occupied by the stiff shank of the sole. When the lacing is drawn the soft leather fits this part of the foot like a glove. The upper may be laced 55 as tightly as desired between the arch and the ankle, the tightness merely binding the arch of the foot more strongly in its curved formation. Instead of the foot being drawn down more tightly to the sole with accom- 60 panying tendency to depress the arch, the flexible under portion of the upper is lifted and drawn upward more closely about the foot. The only part of the footwear under the middle portion of the foot which does 65 not thus rise to the foot is the two close-

together edges of the upper and that trifling portion of the sole which intervenes between them; and these parts are located, according to the invention, beneath the outer side of the foot, *i. e.*, beneath the lower base of the 70 transverse arch, where the under side of the foot normally touches the ground.

Ordinarily it will be necessary for the top of the shoe to be split or open below the apex 16 of the middle transverse arch, as now 75 customary and as shown in Fig. 3, in order for the foot to be inserted; but the lacing represented by eyelets 18 below said apex is not needed to hold the shoe on the foot and might be omitted, the only lacing necessary being that between said apex and the ankle as at 17 for drawing the upper snugly about that portion of the foot. That lacing may be loose enough to be entirely comfortable, owing to the glovelike grasp of the 80 fit. The fore part of the shoe may be loose and larger than the foot if desired without danger of coming off; and the shape of the toe, sole, heel and other parts may be varied at will or as fashion may demand. 90

In shoes having a channeled inner sole as above described, the inner sole is extremely narrow at its shank, and the shank of the outer sole may be correspondingly narrow if desired; but it is preferable, in order to 95 give greater strength to the sole, and to protect from wear the portion of the upper which is under the foot, to make the outer sole wide enough to extend under the major portion of the instep of the foot. The shank 100 of the outer sole is therefore represented in Fig. 3 as of ordinary width; but nearly all of its width might be cut away, as, unlike the arrangement in ordinary shoes, this portion of the sole does not form a part of the 105 band encircling the foot.

I claim:—

1. Footwear having a sole in combination with an upper, both right and left sides of which, at a place between the heel and ball 110 of the foot, are attached to the sole under the outer side of the foot.

2. Footwear having a sole in combination with an upper arranged above it and attached thereto, the right and left sides of which are, at the heel and at the ball of the foot, shaped upward from their respective sides of the sole; and at a place between said heel and ball are shaped upward from under the outer side of the foot. 120

3. Footwear having a sole in combination with an upper, both outer and inner edges of the upper being attached to the sole between the middle transverse arch of the foot and the ankle with approximately no portion of the sole intervening between the lines of their said attachment. 125

4. Footwear having a sole in combination with an upper, and means to hold the upper constricted over the middle transverse arch

- of the foot and to the rear thereof; both outer and inner edges of the upper being attached to the sole approximately under the exterior base of said arch.
5. Footwear having an outer sole in combination with a welt and an inner sole attached thereto, and an upper, the upper being attached to the edges of the inner sole; the inner sole having a deep recess at the instep, thereby forming its shank at the outer side of the foot, and the shank of the outer sole extending under the major portion of the width of the instep of the foot.
6. Footwear comprising a flexible upper fitting over and under the middle transverse arch of the foot and to the rear thereof and having its edges brought in under the foot to approximately surround the foot with the upper, in combination with a sole having approximately the stiffness of sole leather, the upper being attached by its edges to the sole under the wearer's foot at the outer portion thereof approximately along the borders of the tread of a normal shoewearing bare foot.
15. Footwear comprising a flexible upper fitting over and under the middle transverse arch of the foot and to the rear thereof and having its edges brought in under the foot to approximately surround the foot with the upper, in combination with a sole having approximately the stiffness of sole leather, the

upper being attached by its edges to the sole under the wearer's foot.

7. Footwear comprising a flexible upper fitting over and under the middle transverse arch of the foot and to the rear thereof and having its edges brought in under the foot to approximately surround the foot with the upper, in combination with a sole having approximately the stiffness of sole leather, the upper being attached by its edges to the sole under the wearer's foot at the outer portion thereof approximately along the borders of the tread of a normal shoewearing bare foot.

In testimony whereof I hereto affix my signature, in presence of two witnesses.

FRANCIS D. DONOGHUE.
